FOOTBALL FIGURE SAVINGS BANK

Frank Sterba, Jr., 4317 Patterson,
Omaha, Nebr. 68107

Filed Apr. 14, 1975, Ser. No. 568,006

Term of patent 14 years

Int. Cl. D21—01

U.S. Cl. D34—11 R

FIG. 1

FIG. 2

FIG. 3

FIG. 1 is a frontal elevation of a football figure savings bank showing my new design;

FIG. 2 is a left side elevation thereof, the right side elevation being a mirror image thereof;

FIG. 3 is a top plan view of the football figure savings bank; and

FIG. 4 is a bottom plan view of the central part of the football player with the arms not shown.

I claim:

The ornamental design for a football figure savings bank, as shown.
